UNITED STATES PATENT OFFICE.

EDWARD L. WATROUS, OF EL PASO, TEXAS; AGNES B. WATROUS BEING EXECUTRIX
OF SAID EDWARD L. WATROUS, DECEASED.

METHOD OF METAL COATING AND APPARATUS THEREFOR.

1,418,412.

Specification of Letters Patent. Patented June 6, 1922.

Application filed April 24, 1918. Serial No. 230,400.

To all whom it may concern:

Be it known that I, E. L. WATROUS, a citizen of the United States, residing at El Paso, in the county of El Paso and State of 5 Texas, have invented certain new and useful Improvements in Methods of Metal Coating and Apparatus Therefor, of which the following is a specification.

This invention relates to a method and 10 apparatus for metal coating, and more particularly to galvanizing or the like, the articles under treatment, after being coated, being subjected to centrifugal force.

Among the objects of this invention is to 15 render more efficient the process of galvanizing or the like; further to eliminate waste of time, labor, and loss of heat heretofore involved in transferring from the coating bath to a separate and removed centrifugal 20 machine; further to provide a rotatable head which may be readily detached from the rotating shaft for cleaning when it becomes unduly clogged or coated with spelter or other material used for coating, and a 25 clean head substituted in its place; further to provide special apparatus for raising and lowering the basket containing the articles to be galvanized into and out of the spelter bath; further to permit the application of 30 the centrifugal action to which the articles to be galvanized are subjected, directly above the spelter bath so that any superfluous coating material thrown off from the articles may find its way back into the bath; 35 further to render possible the continuous treatment in large quantities of small articles such as nails, tacks, and the like; further to provide a removable basket which may be inserted into or removed from the 40 head; further to provide novel means for introducing articles to be coated into the basket, while the same is immersed in the bath; and such further objects, advantages and capabilities as will later become more 45 readily apparent.

My invention further resides in the combination, construction and arrangement of parts illustrated in the accompanying drawings, and while I have shown therein a preferred embodiment of apparatus for carrying out my new method, I desire it to be understood that the same is susceptible of

modification and change without departing from the spirit of my invention.

In the drawings:

Figure 1 is an end elevation of the apparatus of my invention showing the tank and furnace walls in section.

Figure 2 is a horizontal section taken on the line 2—2 of Figure 1 and looking in the 60 direction of the arrows.

Figure 3 is a side elevation of the rotatable head with the basket therein.

Figure 4 is a view similar to Figure 3 but showing the head as rotated through 90°.

Figure 5 is a sectional detail view showing the mechanism for elevating and lowering the shaft upon which the rotatable head is mounted.

Figure 6 is a detail view of the door latch.

Referring to the drawings, the apparatus of my invention comprises the tank 1 adapted to contain a suitable spelter bath 2 and around which tank is built a masonry wall 3 to provide the space 4 for the reception of coke or the like by means of which the spelter bath is heated. Located in the lower portion of the masonry walls 3 are a plurality of apertures 5, which not only supply draft for the coke fire within the space 4, but also enable the attendant to have access to the fire near the bottom for the purpose of regulating the heat thereof. The tank 1 as seen in Figure 2 is of elongated 80 formation, that portion farthest removed 85 from the rotatable head serving to provide reserve heat. 6 is a sheet iron shell which encloses the rotatable head and serves to catch the flying zinc and deflect it back into the tank. This shell has formed in the face 90

7 a door (not shown) the purpose of which is to give accessibility to the inside of the tank when placing a basket within the rotatable head or removing the same therefrom. Through the shell extends the rotatable shaft 9, upon the lower end of which is mounted the head 10, which is removably attached thereto by means of a suitable bolt 11 or other equivalent means, passing through the block 12. The construction of this rotatable head is as follows:—to the block 12, at opposite sides are secured by means of the bolts 13 and 14 the main straps 15, which, as shown, are formed near each

end with the angular bends 16 and 17, and at their lower portions with the bends 18 and 19 whereby to form a pair of loops as clearly shown in Figures 1, 3 and 4. These 5 members 15, in addition to being bent, as indicated at 16 and 17, are also bent near their upper ends laterally, as shown in Figure 4, at 20 and 21 for the purpose of bringing the upper ends of these straps to 10 the proper position to be bolted to the block 12.

Secured to the members 15 are the members 22 and 23 which as shown are U-shaped and secured at each side of the head to 15 the members 15, thus forming three sides of the head and are left open at their front sides to make provision for hanging a swinging door thereto. Secured to the inner face of the members 22 and 23 20 and at the backside of the head are the vertical members 24, which as shown in Figure 4 extend downwardly to a level with the upper face of the bottom portions of the straps 15 at which point these members 24 25 are formed with a rectangular bend 26, and then extended forwardly to rest upon and be secured to the upper faces of the lower portions 27 of the members 15. It will thus be seen that this head is composed of an open 30 work frame on three sides and the bottom, the fourth side, being left open for the reception of the door member which is hinged to the free end of the members 22 and 23 as indicated at 30. This door is of slat formation 35 and comprises the vertically extending bars 31 and the horizontally extending bars 32 securely fastened together at their crossing points. In order to lock this door in closed position when the head is in operation 40 I have provided the latching means 33 (see Figure 6) which comprises the main arm 34 having the hooked end 35, for cooperation with the similar hook 36 located upon the outer end of the door member 32. This latch 45 33 is pivoted at 34' to a suitable bracket carried by the side members 22 and 23 adjacent their extremity opposite the end to which the door is hinged. In order that this latch may be quickly released I have provided the projecting arm 37 which may be operated by 50 being struck a blow to release the catch 35 from the lip 36. In order to firmly hold this latch means in operative position I have provided the rearwardly extending arm 38 between which arm and adjacent member 22 or 55 23 is positioned a coil spring 39, normally tending to move this latch in clockwise direction. Positioned within the head 10 is the basket 40 which is formed of sheet metal or 60 the like having its sides and bottom perforated and a metal band 41 extending around the top portion thereof for the sake of rigidity and strength. By releasing the latches 33 and swinging the door 32 into open position 65 this basket may be readily placed in po-

sition within the head or removed therefrom. As shown in Figures 1, 3 and 4 a considerable space has been provided between the upper edge of the basket 40 and the lower face of the block 12 whereby to permit the 70 passage therethrough of the nozzle of the spout 42 into position over the open topped basket when the head is in lowered position as indicated in Figure 1. The open work head just described is constructed of metal 75 bars of suitable width and thickness, and the basket 40 of sheet metal of suitable gauge.

Positioned upon each side of the tank and outside of the furnace, as seen in Figures 1 and 2 are the vertical posts or columns 45, 80 between which columns and extending across the top of the tank at a suitable height is the cross-brace 46, and at a suitable distance thereabove the further cross brace 47. The cross brace 47 is formed at one end with an 85 upwardly extending member 48 which terminates in the platform 49, upon which is mounted a suitable motor 50. The cross braces 46 and 47 are each formed at their mid-point with the hub portions 51 and 52 90 respectively, while the outer extremity of the platform 49 is provided with the enlarged portion 53. The hub portions 51 and 52 and the enlarged portion 53 are bored out and which bores fall in alignment with each other 95 and through which passes the vertical shaft 9.

Just above the enlarged portion 53 the shaft 9 is provided with a suitable clutch comprising the portions 54 and 55, by means of which the shaft 9 may be caused to rotate 100 or remain stationary as desired. This clutch is operated by means of a belt 56 suitably connected to the motor 50. It is obvious of course, that I may substitute any other source of motive power and form of clutch if desired. 105

Surrounding the shaft 9 and having longitudinally sliding movement through the bores of the hub 51 and 52 is the sleeve 60 provided upon its exterior with the threads 110 61 extending substantially the full length thereof. Mounted upon the shaft 65 and in engagement with the threads 61 is the spur pinion 64, which is caused to rotate by means of power being transmitted from the handle 66 of the wheel 67 by virtue of the connections therewith through the medium of the shafts 68 and 65 and beveled gears 69, 70 and 71, 72; which beveled gears, shafts and hand wheel are suitably mounted in brackets provided therefor as shown. 115

In order to permit rotation of the shaft 9 within the sleeve 60 and at the same time cause these parts to move longitudinally in unison with each other, it will be seen in 120 Figure 5 that I have provided the oppositely located pins 77 which extend into the circumferential groove 78 formed in the shaft 9. As a result of this arrangement, when the sleeve 60 is elevated or lowered as 125 130

the result of rotation in the appropriate direction of the spur pinion 64, the shaft 9 will have corresponding upward or downward movement but will at the same time 5 be free to rotate within this sleeve.

Secured to one of the upright posts 45 by means of a set screw 79 or other equivalent means is the bracket 80 formed upon one end with the perforated portion 81, to 10 which is pivotally connected the spout or hopper 42, a handle or other suitable projection 82 being provided upon the outer end of the spout 42, whereby to facilitate movement thereof. Formed in the side of 15 the shell 6 and opposite the location of the hopper 42 is the longitudinal opening 83 of sufficient length to permit adequate longitudinal movement therein of the spout or hopper 42 when being swung from position 20 shown in Figure 2 to a rearward position and away from the head 10 to permit rotation thereof. In order to prevent an undue loss of heat through this opening 83 and also any undesirable flying of spelter there- 25 through I have provided means to close this opening but yet permit movement therein of the spout 42. This closing means I have shown as consisting of two sliding plates 84 and 85 which are slidably mounted 30 in suitable guide ways and are normally held in contact with the sides of the spout 42 by means of the coil spring 85 being at- 35 tached at its respective ends to each of these sliding doors and extending under tension therebetween. From this it will be seen that as the spout 42 is moved in the opening 83 the doors 84 and 85 will follow the spout and at all times keep the opening 83 closed.

In the carrying out of my method with 40 the apparatus described above I bring the spelter bath to a suitable temperature and then insert within the head 10 the perforated basket 40. The head during this operation being in elevated position and out of contact 45 with the spelter bath. The head is then lowered so as to become immersed in the spelter bath after which the spout 42 is thrown into the position shown in Figure 2. The articles to be galvanized or other- 50 wise coated may be either thrown by means of a shovel or the like into the spout 42, or if desired they may be fed there into by means of gravity in an obvious manner. The articles thus passed through the spout 42 55 will be sprinkled upon the surface of the spelter bath within the basket, and by regulating the quantities fed through the spout 42 they will separately sink in the spelter bath within the basket and individually take 60 their coating. This is a great advantage over throwing them in large masses or bunches within the immersed basket for the reason that such masses or bunches would cause the spelter to become clogged around 65 the exterior and freeze within the interstices

before it reached the center of the mass, thus leaving the center black and uncoated. Any small masses thus floating should be thrust under the surface with a skimmer until they separate and sink. After the 70 articles are sprinkled in the immersed basket the spout 42 is then moved rearwardly away from the head a suitable distance, after which the surface will be skimmed, the head will be elevated by means of rotation of the 75 hand wheel 67, which as described above will impart rotation to the pinion 64 and by virtue of its engagement with the threads 61 of the shaft 60, the shaft 9 will be ele- 80 vated, thus lifting the head 10 out of the spelter bath. The doors are then closed, the shaft and head rotated by means of the motor 50, and any excess coating material on the articles within the basket will be thrown therefrom by centrifugal force, it not yet 85 having solidified, and striking the sides of the shell will be deflected back into the tank. The basket may then be removed from the head, its contents emptied and either the same or another basket inserted into the 90 head and the operation repeated, thus making possible the continuous galvanizing in large quantities of the articles to be coated. Articles coated and treated in this manner 95 will have a smooth uniform coating, entirely free from undesirable excrescences, projections, blisters or the like.

After use for a certain length of time the head 10 is liable to become clogged up with the spelter or other coating material at which 100 time it may be quickly removed by withdrawing the bolt 11 and slipping the block 12 and the attached head off of the lower end of the shaft 9. The head may then be thrown into a pickling bath or otherwise 105 treated for cleansing and a clean head substituted therefor, thus permitting the operation to be continued and a clean head always available.

I claim:

1. In galvanizing apparatus, a tank for containing a spelter bath, a detachable receptacle to hold the articles to be coated, a depending removable hollow head to slidably receive said receptacle within itself, 115 means for immersing said receptacle in said bath and removing the same therefrom, and means for rotating said receptacle above said bath.

2. In galvanizing apparatus, a tank for containing a spelter bath, a detachable receptacle to hold the articles to be galvanized, a depending, removable, hollow head to slidably receive said receptacle within itself, 120 means for lowering and elevating said receptacle into and out of said bath, and means for rotating said receptacle above said bath, whereby to remove by centrifugal force the surplus coating from said articles.

3. In galvanizing apparatus, a tank for 130

containing a spelter bath, a longitudinally movable shaft, a depending removable open work head on said shaft adapted to be lowered into and raised from said bath, a perforate container adapted to contain articles to be galvanized and to be placed in said head, and means to cause said shaft to rotate whereby to rotate said head above said bath.

4. In galvanizing apparatus, a tank for containing a spelter bath, means for heating said bath, a longitudinally movable shaft, a depending removable open work head on said shaft adapted to be lowered into and raised from said bath, a foraminated basket adapted to be inserted into and removed from said head, and means to cause said shaft to rotate whereby to rotate said head above said bath.

5. In galvanizing apparatus, a longitudinally movable shaft having a detachable head thereon adapted to be lowered into a spelter bath and elevated therefrom, and means for sprinkling the articles to be galvanized into said head while immersed in said bath.

6. In galvanizing apparatus, a longitudinally movable shaft having a detachable head thereon adapted to be lowered into a spelter bath and elevated therefrom, means for sprinkling the articles to be galvanized into said head while immersed in said bath, and means for rotating said shaft whereby to cause said head to rotate above said bath.

7. In galvanizing apparatus, a tank for containing a spelter bath, a frame work above said tank provided with aligned bores, a threaded sleeve slidably mounted in said bores, means in engagement with said sleeve

to transmit longitudinal movement thereto, a shaft rotatably mounted in said sleeve but fixed to move longitudinally therewith, means to rotate said shaft, and a detachable head on the lower end of said shaft adapted to be lowered into said spelter bath and be rotated thereabove.

8. In galvanizing apparatus, a tank for containing a spelter bath, a rotatably and longitudinally movable shaft entering said tank, means to rotate said shaft, means to move said shaft longitudinally, an open work head detachably connected with said shaft, a foraminous open top basket adapted to be inserted into and removed from said head, and means for securing said basket in said head during rotation.

9. In apparatus of the class described, a tank containing a spelter bath and having an open topped wall, extending vertically from the top of the tank, a vertical shaft, an open work head, removably mounted on the lower end of said shaft, adapted to be rotated in said open topped wall, means for lowering said head into said bath, and elevating the same therefrom, and means for rotating said head within said wall whereby to remove by centrifugal force any excess coating material from the articles being coated and confine the same within the wall.

In witness whereof, I hereunto subscribe my name to this specification in the presence of two witnesses:

EDWARD L. WATROUS.
